UNITED STATES PATENT OFFICE.

FRANK P. SPARMAKER, OF PHILADELPHIA, PENNSYLVANIA.

DESIGN FOR A WATCH-CHARM.

[SPECIFICATION forming part of Design No. 21,749, dated August 2, 1892.

Application filed July 2, 1892. Serial No. 438,829. Term of patent 3½ years.

To all whom it may concern:

Be it known that I, FRANK P. SPARMAKER, a citizen of the United States, and a resident of Philadelphia, Pennsylvania, have invented a new and original Design for a Watch-Charm, of which the following is a specification.

My design for a watch-charm is fully shown in the accompanying drawings, in which—

Figure 1 represents the obverse and Fig. 2 the reverse.

The obverse of the design presents two segments A and B, the dividing-line being partly curved, as at *a*, and partly radial, as at *b b*. On the central portion of the segment A are parallel columns, and on the segment B are radiating columns extending from the tops of said parallel columns of the segment A.

The reverse of the design has a circular body with radial slots *g*, *i*, and *i'*. Above the slotted portion are representations of the different phases of the moon, and below said slotted portion are mountain landscapes with representations of a rising and a setting sun.

Both the obverse and the reverse of the charm have the ornamental top band *d* and 25 ring or loop *f*.

I claim—

1. The design for a watch-charm, substantially as described, and as illustrated in the accompanying drawings. 30
2. In a design for a watch-charm, the design for the obverse, substantially as described and shown.
3. In a design for a watch-charm, the design for the reverse, substantially as described and 35 shown.

In testimony whereof I have signed my name to this specification in the presence of two subscribing witnesses.

FRANK P. SPARMAKER.
